(57) **CLAIM**

The ornamental design for an optical drive cushion made of biodegradable, recycled paper pulp, as shown and described.

DESCRIPTION

FIG. 1 is an elevated isometric view of an optical drive cushion made of biodegradable, recycled paper pulp showing my new design;

FIG. 2 is a bottom isometric view thereof;

FIG. 3 is a top isometric view thereof;

FIG. 4 is a right side or left side view thereof;

FIG. 5 is a top view thereof;

FIG. 6 is a bottom view thereof;

FIG. 7 is a front or rear view thereof; and,

FIG. 8 is a front isometric view thereof with an optical drive and second optical drive cushion in phantom.

The broken lines in the FIG. 8 depict environmental subject matter only and form no part of the claimed design.
